UNITED STATES PATENT OFFICE.

JOHANNES R. CARLSON, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

Application filed December 7, 1922. Serial No. 605,437.

To all whom it may concern:

Be it known that I, JOHANNES R. CARLSON, a citizen of the United States of America, residing at Hartford, in the county of Hartford and State of Connecticut, have invented certain new and useful Improvements in Electric Switches, of which the following is a specification.

My invention relates to electric switches, and particularly to rotary snap switches. The object of my invention is to provide an improved switch blade carrier and assembly unit, which is per se not only of substantial and rugged structure, but also economical to manufacture, while the unit, as such, facilitates its assembly with the associated elements of the switch mechanism.

In the accompanying drawings—

Fig. 1 is a vertical section through a switch in which my invention is embodied in one form;

Fig. 2 is a partial section through the switch blade unit alone on the spindle;

Fig. 3 is a broken plan view thereof;

Fig. 4 is a broken section on the line 4—4, Fig. 2;

Fig. 5 is a broken perspective of the carrier in condition for the reception of the switch blades; and

Fig. 6 is a plan view of the blank from which the carrier is formed.

Inasmuch as the subject matter of the present application is restricted to the switch blade carrier unit, the remaining details of the construction need not be described at length. It suffices to point out that in the form illustrated the invention is applied to a switch of the heater-circuit control type, comprising an insulating base 7 from which rises the switch spindle 8 actuated by the handle 9 and operating an escapement mechanism generally indicated by the reference 10. The spindle 8 drives the switch spring 11 through the plate 12, while the mechanism as a whole is enclosed in a switch cover 13 with insulating lining 14.

The switch blades 15, of which two are here shown, are mounted upon a carrier, which with its rigidly associated elements, forms the feature of the switch mechanism to which the invention particularly relates. The body of the carrier is shaped from the sheet metal blank illustrated in Fig. 6, comprising the four arms 16, 17, 18 and 19 radi-

ating from, and integral with, the central area 20. The arms 18 and 19 are cut away at 21 and 22 to accommodate the marginal areas of the corresponding portions of the arms 16 and 17, when the several arms are bent along the lines 23 to form the rectangular body of the carrier. The extremities of the arms 18 and 19 are oppositely bent along the lines 24 to form offset foot pieces 25. The reduced extremities of the arms 16 and 17 are offset, similarly, in the same plane by bending along the lines 26 to form associated foot pieces 27. The carrier thus presents a rugged body element of rectangular cross section, the sides of which are held rigidly in interlocked relation by washer 28, the aperture in which is closely shaped to the rectangular contour of the carrier body so that when forced down over the head of the carrier and against the foot pieces 25 and 27 it effectively retains the arms in fixed position. It will be observed that the edges of the reduced portions of arms 18 and 19 form abutments against which the marginal areas of arms 16 and 17 abut; and that the reduced areas of arms 16 and 17 have the same function with respect to the arms 18 and 19. Precision of relative position is thus assured.

A punching 29 in the central web of the blank affords a top bearing for the carrier on the switch spindle 8. A bottom bearing is afforded by the latch plate 30. As here shown, the latch plate is shaped to afford a pair of arcuate wings 31 and 32 adapted to cooperate with the detaining studs 33 of the escapement mechanism, which is of the type illustrated in the copending application of William H. Harrington, filed November 27th, 1922, Ser. No. 603,583, patented August 28, 1923, under No. 1,466,507, to which reference may be had for the details of this device. The latch plate is preferably tempered to withstand the repeated impacts to which it is subjected by the operation of the switch. It is secured to the blade carrier by studs 34, which are forced up from the latch plate and shaped to afford a drive fit in holes 35 and 36 in the offset foot pieces 25 of the carrier.

The switch blades 15 are provided with central rectangular apertures generally corresponding in shape to the outline of the body of the carrier, but of sufficiently greater size to accommodate interposed insulation

37 of any suitable character. The blades are spaced apart on the switch spindle by interposed plates of insulation 38 and spacing washers 39, by which their exact location 5 with reference to the associated contacts (not shown) on the switch base 7 may be attained.

Overlying the upper blade and its superposed insulating disk 38, is a contact driving plate 40 having an offset dog 41 which is engaged between the ends of the switch spring 11. The driving plate 40 has a rectangular aperture, which snugly fits the body of the carrier, so that the carrier and 15 switch blade move therewith. In order to unite the several parts into a rigid assembly unit, the head 20 of the carrier is staked at 42 over the driving plate.

The construction is rugged and strong, 20 while at the same time it is simple to manufacture and provides an assembly unit which may be conveniently handled and positioned upon the switch spring by the operative during the assembly of the switch. 25 The full spring value of the switch blades is obtained since they are restrained only by the relatively narrow spacing washers 39 which overlie the central web portions of the blades. The exact spacing and alignment 30 of the blades is permanently assured by the staking over of the head of the carrier, which unites the parts into a rigid column. The interior of the carrier forms a reservoir 43 for the reception of lubricant, which is thus constantly supplied to the spindle passing therethrough. The connection to the escapement plate is conveniently effected through the offset foot pieces 35 of the blade carrier. Just what form this connection takes, or what type of escapement 40 is employed, is immaterial. Of course the particular construction of escapement plate will vary with the different types of escapement with which the blade carrier 45 is used.

Various modifications in details of proportion and structure will readily occur to those skilled in this art, without departing from what I claim as my invention.

50 I claim—

1. In an electric switch, a switch blade carrier comprising a top web apertured to afford a spindle bearing and having integral arms offset therefrom to form a polygonal carrier body, certain of said arms having outwardly offset foot pieces, in combination with a bottom plate apertured to afford a spindle bearing and operatively connected to said offset foot pieces.
- 60 2. In an electric switch, a switch blade carrier comprising a top web apertured to afford a spindle bearing and having integral arms offset therefrom to form a polygonal carrier body, certain of said arms having 65 outwardly offset foot pieces, in combi-

nation with a bottom plate apertured to afford a spindle bearing and operatively connected to said offset foot pieces, said bottom plate being shaped to cooperate with the detaining latches of an escapement 70 mechanism.

3. In an electric switch, a switch blade carrier, comprising a polygonal body having an outwardly extending foot, switch blade means fitting upon and surrounding said 75 carrier body, a top plate overlying said switch blade means and having a driving engagement with the carrier body, together with means rigidly securing said top plate in position on said carrier.

4. In an electric switch, a switch blade carrier, comprising a top web apertured to afford a spindle bearing and having integral arms offset therefrom to form a polygonal carrier body, certain of said arms having outwardly offset foot pieces, in combination with a bottom plate apertured to afford a spindle bearing and operatively connected to said offset foot pieces, said bottom plate being shaped to cooperate with the detaining latches of an escapement mechanism, 80 said top plate having means for engaging a driving spring.

5. In an electric switch, a switch blade carrier, comprising a polygonal body having an outwardly extending foot, switch blade means fitting upon and surrounding said carrier body, a top plate overlying said switch blade means and having a driving engagement with the carrier body, together 95 with means rigidly securing said top plate in position on said carrier, and means for insulating said switch blade means from the carrier and top plate.

6. In an electric switch, a switch blade carrier comprising a sheet metal body having offset and apertured foot pieces, in combination with a tempered escapement plate underlying said foot pieces and having studs entering the apertures in the foot pieces of the carrier body to afford an operative connection between the parts.

7. In an electric switch, a switch blade carrier comprising a sheet metal body having offset and apertured foot pieces, in combination with a tempered escapement plate underlying said foot pieces and having integral studs entering with a drive fit the aperture in the foot pieces of the carrier body.

8. In an electric switch, a switch blade carrier comprising a sheet metal web having integral legs offset to form a polygonal body element of the carrier and outwardly extending foot pieces, together with a holding washer having an aperture shaped to said polygonal body and passed down over said legs and against the foot pieces to hold said legs in definite relation to each other.

9. In an electric switch, a switch blade carrier comprising a sheet metal web hav-

ing integral legs offset to form a polygonal body element of the carrier and outwardly extending foot pieces, together with a holding washer having an aperture shaped to said polygonal body and passed down over said legs and against the foot pieces to hold said legs in definite relation to each other, said legs being marginally recessed to interfit and afford mutual abutments limiting their displacement toward the axis of the carrier.

10. In an electric switch, a switch blade carrier comprising a sheet metal web having integral legs offset to form a polygonal body element of the carrier, and outwardly offset foot pieces, a washer passed over the body of the carrier and resting against said foot pieces to hold the sides of the body against displacement, switch blade means 15 passed freely onto the carrier body, a top plate overlying the switch blade means, the top web of the carrier being apertured to afford a spindle bearing and being staked over said top plate to secure the parts rigidly together, together with an escapement plate underlying the carrier foot pieces 20 and operatively engaged therewith, said escapement plate being apertured to afford a bottom bearing for the carrier unit.

over said top plate to secure the parts rigidly together.

11. In an electric switch, a switch blade carrier comprising a sheet metal web having integral legs offset to form a polygonal body element of the carrier, and outwardly offset foot pieces, a washer passed over the body of the carrier and resting against said foot pieces to hold the sides of the body against displacement, switch blade means passed freely onto the carrier body, a top plate overlying the switch blade means, the top web of the carrier being apertured to afford a spindle bearing and being staked over said top plate to secure the parts rigidly together, together with an escapement plate underlying the carrier foot pieces 30 and operatively engaged therewith, said escapement plate being apertured to afford a bottom bearing for the carrier unit.

In testimony whereof I have signed my name to this specification.

JOHANNES R. CARLSON.
